*Victor E. Baier,
Attorney.*

UNITED STATES PATENT OFFICE.

VICTOR MAUCK, OF NORRISTOWN, PENNSYLVANIA.

GAS WATER HEATER.

1,416,487.

Specification of Letters Patent. Patented May 16, 1922.

Application filed July 9, 1921. Serial No. 483,449.

To all whom it may concern:

Be it known that I, VICTOR MAUCK, a citizen of the United States, residing at Norristown, in the county of Montgomery and State of Pennsylvania, have invented a certain new and useful Improvement in Gas Water Heaters, whereof the following is a specification, reference being had to the accompanying drawings.

10 My invention relates to gas water heaters of the type known to the trade as automatic combination range boilers and including a cylindrical casing for the gas burner, which casing is partitioned above the burner to 15 form a water tank with a central flue for products of combustion from said burner, and having a valve for the gas supply controlled by a thermostat extending in the water tank, so that the flow of gas to the 20 burner is controlled in accordance with the temperature of the water heated by the burner.

However, as hereinafter described, my invention relates more particularly to the construction and arrangement of said casing, which is termed the boiler shell.

25 My invention includes the various novel features of construction and arrangement hereinafter more definitely specified. However, the specific form of container herein disclosed is claimed in my copending application Serial No. 512,763, filed November 4, 1921, for Letters Patent of the United States.

30 In said drawings: Fig. I is a diagrammatic perspective view of an automatic combination range boiler and gas water heater embodying my invention.

Fig. II is a plan view of the boiler shell indicated in Fig. I.

Fig. III is a front elevation of such a boiler shell.

Fig. IV is a vertical central sectional view of the boiler shell shown in Fig. III.

Fig. V is a transverse plan sectional view, taken on the line V in Figs. III and IV.

Fig. VI is a transverse plan sectional view, taken on the line VI in Figs. III and IV.

50 In said figures; the cylindrical tubular casing shell 1 has the door opening 2 in its circumference, near the lower end thereof. The outwardly projecting circumferential bead 3 is formed in said shell above said opening. The two outwardly projecting circumferential beads 5 and 6 are formed in

said shell below said opening, and the longitudinal beads 7 at opposite sides thereof; whereby said shell is reinforced at said opening, without the employment of the separate auxiliary stiffening plates or rings, which are characteristic of devices of the prior art. Consequently, the required degree of stiffness of said shell, at the region of the doorway 2, is secured at less cost than by the employment of such auxiliary devices.

The cylindrical tubular flue 8 extends in coaxial position in said shell 1, the full length of the water compartment 9, which compartment is formed between said shell 1 and flue 8. Said water compartment is closed at the top end of said shell by the upwardly convexed head 10 having the downwardly extending cylindrical flange 11 fitting in said shell. Said water compartment 9 is closed, intermediate of the length of said shell 1, by the downwardly convexed partition 13 having the downwardly extending cylindrical flange 14 fitting in said shell, adjacent to said upper bead 3. The burner compartment 16 in said shell, which is primarily open at the bottom thereof, as indicated in Fig. IV, is formed by the skirt portion 17 of said shell, extending below said partition 13 and including said door opening 2. Flat places 20 and 21 are formed in said shell, interrupting the normally cylindrical configuration thereof, as shown in Figs. IV and V. It may be observed that said two flat places 20 and 21 extend in a common plane which is tangential to a circle 22 concentric to the axis of said shell 1 and flue 8, but of a diameter intermediate of the diameters of said shell 95 and flue, for the purpose hereinafter described. Three flat places 23, 24 and 25 are formed in said head 10, which are in a common plane interrupting the normal convex configuration of said head, as indicated in Fig. IV, at right angles to the axis of said shell 1 and flue 8.

One flat place 26 is formed in said partition 13, in a plane at right angles to the axis of said shell 1 and flue 8, interrupting the normal convex configuration of said partition, as indicated in Fig. IV. Six similar pipe spuds 27 are respectively secured at said six flat places formed in said shell, head, and partition.

All of the parts above described are assembled in integral relation, conveniently by welding them together, by means of an

oxyacetylene burner, and such shells with the integral appurtenances above described are articles of commerce, independently of such equipment as may be applied thereto 5 to form a gas water heater.

However, I have shown in Fig. I, a convenient embodiment of such an article of manufacture as a combination range boiler and gas water heater. In that figure; said 10 shell 1 is provided with the door frame 30 rigidly connected therewith in registry with said opening 2, between said reinforcing beads 3 and 5. Said frame 30 has the door 15 31 hingedly connected therewith by the pintle 32 extending through opposed lugs on said frame and door. The bottom of said shell 1, which is primarily open as best shown in Fig. IV, is arranged to be closed by the diaphragm 33 at the top of the 20 supporting stand 34, which stand is conveniently provided with three legs 35, and the shell holding flange 36.

As shown in Fig. I; cold water is supplied to said water compartment 9 through 25 the inlet pipe 37 and passes downward through the spud at 26 to the water spreader 38 where it is instantly heated and rises upwardly through the pipe 39 which extends in said flue 8 in coaxial relation with said 30 shell 1, but branches outwardly through the vent pipe 40 into the Y fitting 41 which has branches connected with the spuds at 24 and 25 and is connected with the pipe 43, leading to the hot water faucets or other dispensing fixtures. Under ordinary conditions, the auxiliary burner 45 furnishes ample heat for said water spreader 38; getting its supply of gas through the by-pass 46. However, when cold water is caused to 40 enter said compartment 9, by drawing off hot water through said pipe 43, the thermostatic valve 48 opens automatically and gas is delivered through the pipe 49 to the burner 50 and ignited by said auxiliary 45 burner 45. When the water is restored to the temperature for which said automatic valve 48 is set, for instance, 130° Fahrenheit, said valve 48 automatically closes, extinguishing said main burner 50, and remains closed until the next influx of cold 50 water is caused by withdrawing hot water through said pipe 43.

The thermostatic element 52, of said valve 48, extends axially through the spud at 21; 55 its axis being indicated by the dash line in Fig. V, tangential to a circle concentric with the axis of said shell 1 and flue 8, and larger than the circumference of said flue, so that said thermostatic element 52 does 60 not come in contact with said flue.

The spud indicated at 20 in Fig. IV may be used to connect said water compartment 9 to the water-back in a coal range or furnace for winter operation, by means of the 65 pipe 55; the other connection to said water

back being made by the pipe 56 which extends through the side of said shell 1 in connection with said spreader 38, as indicated in Fig. I.

I have found it convenient to form such containers as indicated at 1, by cutting rectangular blanks from plane sheet metal; punching the doorway 2 therein and forming said reinforcements 3, 5, 6 and 7 by the same pressing operation, while the metal is 70 flat; and thereafter rolling said blank to cylindrical form and uniting its longitudinal edges so as to form a seamless tube, to which the other parts above described are subsequently united so as to form the unitary sheet metal structure shown in Figs. II to VI inclusive. It may be observed that 75 said reinforcements 3, 5, and 6 are annular with respect to the axis of that structure, and that said doorway 2 is surrounded by 80 an annular reinforcement, of which the beads 3, 5 and 7 are components, as indicated in Fig. III. Moreover, it is to be noted that 85 although when said beads are pressed in said plane sheet they are concavo-convex and extend straight in said sheet; when said sheet is rolled to cylindrical form, said beads remain concavo-convex but then extend in 90 toric form.

However, it is to be understood that my 95 improvements, embodied in the container shown in Figs. II to VI inclusive, may be included in gas water heaters of other types than that shown in Fig. I, or in containers differing from that shown. Therefore, I 100 do not desire to limit myself to the precise details of construction and arrangement herein set forth, as it is obvious that various modifications may be made therein, without departing from the essential features of my 105 invention, as defined in the appended claims.

I claim:

1. In a gas water heater, the combination with a cylindrical tubular casing shell, having a door opening in its circumference, near the lower end thereof; of an outwardly projecting circumferential bead formed in said shell above said opening, and two outwardly projecting circumferential beads formed in said shell below said opening, whereby said shell is reinforced at said opening; of a cylindrical tubular flue in coaxial position in said shell; a water compartment formed between said shell and flue, closed at the top end of said shell by an upwardly convexed head, with a downwardly extending cylindrical flange fitting in said shell; said water compartment being closed intermediate of the length of said shell, by a downwardly convexed partition, with a downwardly extending cylindrical flange fitting in said shell, adjacent to said upper bead; a burner compartment in said shell, open at the bottom thereof, formed by the skirt portion of said shell extending below said 125

- partition, and including said door opening; flat places, formed in the curved walls of said shell, head, and partition; and pipe spuds respectively secured at said flat places; the axes of said spuds in said head and partition being parallel with the axis of said shell, and the axes of said spuds in said shell being in a plane at right angles to the axis of said shell; said spud axes being tangential to respective circles, concentric with said shell and flue axis, smaller in diameter than said shell, but larger in diameter than said flue; all of said elements being welded in integral relation.
2. In a gas water heater, the combination with a cylindrical tubular casing shell, having a door opening in its circumference, near the lower end thereof; of an outwardly projecting circumferential bead formed in said shell above said opening, and an outwardly projecting circumferential bead formed in said shell below said opening, whereby said shell is reinforced at said opening; of a cylindrical tubular flue in coaxial position in said shell; a water compartment formed between said shell and flue, closed at the top end of said shell by a head; said water compartment being closed intermediate of the length of said shell, by a partition; and a burner compartment in said shell, open at the bottom thereof, formed by the skirt portion of said shell extending below said partition, and including said door opening.
3. In a gas water heater, the combination with a cylindrical tubular casing shell, having a door opening in its circumference, near the lower end thereof; of an outwardly projecting circumferential bead formed in said shell above said opening, and an outwardly projecting circumferential bead formed in said shell below said opening, whereby said shell is reinforced at said opening; of a cylindrical tubular flue in coaxial position in said shell; a water compartment formed between said shell and flue, closed at the top end of said shell by a head; said water compartment being closed intermediate of the length of said shell, by a partition; and a burner compartment in said shell, open at the bottom thereof, formed by the skirt portion of said shell extending below said partition, and including said door opening; flat places, formed in said shell; and pipe spuds respectively secured at said flat places; the axes of said spuds in said shell being in a plane at right angles to the axis of said shell; said spud axes being tangential to respective circles, concentric with said shell and flue axis, smaller in diameter than said shell, but larger in diameter than said flue; all of said elements being integrally connected.
4. In a gas water heater, the combination with a closed cylindrical tubular casing shell, having a door opening in its circumference, near one end thereof; of a circumferential bead formed in said shell above said opening, and two circumferential beads formed in said shell below said opening, whereby said shell is reinforced at said opening, each of said beads being concavo-convex and extending in toric form in said shell; of a cylindrical tubular flue in coaxial position in said shell; a water compartment formed between said shell and flue, closed at the top end of said shell by a head; said water compartment being closed intermediate of the length of said shell, by a partition; and a burner compartment in said shell, open at the bottom thereof, formed by the skirt portion of said shell extending below said partition, and including said door opening.
5. In a gas water heater, the combination with a closed cylindrical tubular casing shell, having a door opening in its circumference; of an outwardly projecting circumferential bead formed in said shell above said opening, and two outwardly projecting circumferential beads formed in said shell below said opening, whereby said shell is reinforced at said opening, each of said beads being concavo-convex and extending in toric form in said shell; of a cylindrical tubular flue in coaxial position in said shell; a water compartment formed between said shell and flue, closed at one end of said shell by a head; said water compartment being closed intermediate of the length of said shell, by a partition, adjacent to one of said beads; and a burner compartment in said shell, open at the bottom thereof, formed by the skirt portion of said shell extending below said partition, and including said door opening.
6. In a gas water heater, the combination with a closed cylindrical tubular casing shell, having a door opening in its circumference, near one end thereof; of a circumferential bead formed in said shell above said opening, and a circumferential bead formed in said shell below said opening, whereby said shell is reinforced at said opening, each of said beads being concavo-convex and extending in toric form in said shell; of a cylindrical tubular flue in coaxial position in said shell; a water compartment formed between said shell and flue; said water compartment being closed intermediate of the length of said shell, by a partition; and a burner compartment in said shell, open at the bottom thereof, formed by the skirt portion of said shell extending below said partition, and including said door opening.

intermediate of the length of said shell, by a partition, fitting in said shell adjacent to said upper bead; and a burner compartment in said shell, open at the bottom thereof, formed by the skirt portion of said shell extending below said partition, and including said door opening.

7. In a gas water heater, the combination with a closed tubular casing shell, having a door opening in its circumference, near one end thereof; of a circumferential bead formed in said shell adjacent to said opening, whereby said shell is reinforced at said opening; said bead extending in toric form in said shell; a tubular flue in coaxial position in said shell; a water com-

partment formed between said shell and flue; said water compartment being closed intermediate of the length of said shell, by a partition, adjacent to said door opening; and a burner compartment in said shell, formed by the skirt portion of said shell extending below said partition, and including said door opening.

In testimony whereof, I have hereunto signed my name at Conshohocken, Pennsylvania, this eighth day of July, 1921.

VICTOR MAUCK.
